STYPTIC ATTACHMENT FOR RAZORS

Simon Sarch Cesar, London, England

Application January 25, 1949, Serial No. 72,714
In Great Britain March 3, 1948

2 Claims. (Cl. 30—90)

1

This invention relates to devices for attachment to the handles of safety razors and more particularly to devices by means of which a styptic element may be combined with said handles, and it has for its object to provide means for enabling a styptic to be applied to a cut instantaneously, and to this end it is proposed to form the device of a metal or other suitable sleeve forming a casing, means for supporting a styptic element in said casing, and a plurality of spring fingers provided on said casing by means of which said device when slipped on the end of the handle of a safety razor may be secured in position.

Figure 1 is a perspective view of a safety razor illustrating a holder constructed according to one embodiment of this invention.

Figure 2 is a longitudinal section of the device illustrated in Figure 1 drawn to an enlarged scale.

Figure 3 is a section on line III—III of Figure 2.

Figure 4 is a side elevation illustrating a further embodiment of the device.

Figure 5 is an end view thereof.

Figure 6 is a longitudinal section of a still further embodiment of the device.

Figure 7 is a section on line VII—VII of Figure 6.

In the embodiment illustrated in Figures 1, 2 and 3 of the drawing, 1 is the handle of a safety razor provided with a circumferential groove 2 near its free end.

The holder for a styptic element 3 comprises a substantially cylindrical shell or sleeve 4 which may be formed from a strip of resilient sheet material, the longitudinal edges 5 of the bent strip being left free to move relatively when the sleeve 4 is radially expanded against its spring action.

The styptic element 3, which comprises a spherical ball, is rotatably mounted at one end of the shell 4, and may be provided with a through bore for the passage of a pivot pin 6, while the other end of the cylindrical shell 4 is extended to form a number of spring fingers 7 which may be slipped on the free end of the handle of a safety razor to secure the device on said handle each finger 7 is formed with a plurality of inwardly projecting undulations 8 near its root, so as to form stepped resilient shoulders designed to serve as a stop for the end of the handle and to prevent side wobble, and one or the other of said undulations will enter the groove 2 in the razor handle and thus give further support to the device. A clamping ring 9 cooperates with the fingers 13 to lock the device on the razor handle 1, the fingers 7 being preferably serrated or other-

2

wise roughened to increase resistance to accidental movement of the ring 9.

The inwardly projecting undulations 8 also serve to accommodate handles of varying diameters whether provided with an annular groove or not.

A lid, or cover, by which the styptic element 3 may be covered when not in use, is formed as a hemi-spherical cap 10, and in the illustrated embodiment the pivot pin 6 which carries the ball-shaped styptic element 3 is mounted in this cap 10, which itself is pivoted in the shell 4 by means of a pair of trunnions 11 which are formed on the cap and engage holes in the shell 4.

15 With this arrangement the cap 10 can be tilted from a closed position into an open position in which it is accommodated in the shell 4, behind the styptic element 3 so as not to interfere with the use of the styptic.

20 A lip or handle 12 is provided at the edge of the lid 10 and arranged to engage one or the other of two recesses 13 at the outer edge of the shell 4 for limiting the pivotal movement of the lid and, if desired, to produce a clip action with the recesses 13.

25 Figures 4 and 5 and 6 and 7 respectively illustrate simplified forms of the invention in which the clamping ring 9 is omitted, the spring action of the spring fingers being relied upon for holding the device on a razor handle.

In the embodiment illustrated in Figures 4 and 5, the fingers 14 have a single depression or corrugation 15 for engagement with the end portion of the razor handle 1, with or without a groove 30 2, the free ends 16 of said fingers being folded over or otherwise rounded. The styptic element 3 is supported by a pair of dimples 18 formed in the cap 10 arranged to enter suitable recesses provided in the styptic element 3 thus replacing the pivot pin 6.

35 In the modified form of the invention illustrated in Figures 6 and 7 the razor handle 1 is not provided with a groove, and the fingers 19 are formed with a single depression 20 arranged 40 to grip the handle 1 adjacent the end, and with cut-out auxiliary resilient tongues 21 arranged to press on the handle 1 to give additional support for the device.

45 What I claim is:

50 1. A styptic element attachment for the handles of safety razors comprising a short length of tubing forming a casing, a spherical styptic element, means for rotatably supporting said styptic element in the casing so that it projects from one end thereof, a hemi-spherical cover pivotally

mounted at that end of the casing for protecting the styptic element when not in use, and a plurality of spring fingers provided on the other end of said casing for securing the attachment in position on the end of the handle of a safety razor.

2. A styptic element attachment for the handles of safety razors comprising a short length of tubing forming a casing, a plurality of spring fingers provided on one end of said casing for securing it in position on the end of the handle of a safety razor, a hemi-spherical cover pivotally mounted at the other end of said casing, two diametrically opposed inwardly directed projections on said cover and a spherical styptic element hav-

ing two diametrically opposed dimples therein for receiving said projections to hold the styptic element in position.
